LATCHING DEVICE

Harry A. Knauff, Pittsburgh, Pa.

Application April 9, 1957, Serial No. 651,737

4 Claims. (Cl. 292—241)

This invention relates to a lock, latch or fastening device of a type to be used with a keeper part to secure together a pair of adjacently-positioned sash, rail, frame or other members, such as window members, and particularly to a device of a type that functions through its operating stem to produce a tightening wedging action.

The present construction relates to a type that represents a high quality device for safe and sure burglar-proof usage and which has high position-retaining strength characteristics and, at the same time, has a smooth and easy type of operation.

This application is a continuation-in-part of my co-pending application Serial No. 519,597, entitled Latch and filed July 1, 1955, now abandoned.

I have found that the keeper and particularly the latch parts have a better strength and otherwise better conform to requirements when made of cast metal. However, I have encountered difficulty in endeavoring to provide a suitable fastening device having a latch part, due to the limitations as to cast shapes and particularly, due to the difficulty of not only making a substantially hollow or partially closed-in-shape, but in suitably internally machining such a shape to meet requirements.

Previously, I developed the principle of providing a locking type of wedging action against an outer side face of the latch housing to prevent an unauthorized opening or releasing of a latched relationship between a latching part and its associated keeper part. Although I found that a supporting boss projecting downwardly from the top of a support housing body was sufficient for mounting and operating an ordinary latching part or element, with the advent of an external, wedging-locking type of device, I determined that the outside-applied wedging action tended to impose a lever action upon the stem that centered or concentrated about the connecting portion thereof that lies adjacent to the operating handle.

In a later improved construction, I conceived the idea of providing a housing of one-piece construction having vertically spaced-apart or opposed upper and lower mounting portions for the stem and a latch element operated thereby. As a result, a two-point area of support was provided. The upper point was provided by mounting of the stem within the latch housing. The lower point was provided by a cooperating boss on an opposed bottom portion of the housing and which engaged within the latch element, itself. Thus, the stem has, through the latch element, a spaced-apart support that eliminates breakage and importantly, the possibility of a burglar-inspired unlocking when the device is in a fully or partially latched position.

Although those skilled in the art have felt that it is necessary to have the support applied directly to the operating stem, I found that even better results were obtained by a so-called indirect, two-way mounting, as effected through the latch element, etc. It first appeared to be desirable to provide a latch housing made up of a one-piece construction comprising a wedge-locking upright side wall, and opposed top and bottom walls. However,

2

due to the sloped semi-circular nature of the upright side wall and the need for only a small, one-side opening in the housing body (for the latch to engage the keeper), the casting operation became too intricate and expensive for production-line manufacturing techniques. Also, too many rejects were produced, and another problem was raised.

This latter problem involved the need for internally machining-down and providing a relatively accurate bearing face between at least a bottom face of the latch element and an opposed supporting face of the bottom wall of the latch housing. This was found to be essential to provide a smooth and easy operation of the device by an authorized operator, and in spite of a relatively greater weight and strength of structure. In this connection, a smooth, planar bearing under face-to-face relationship between the latch element and the bottom wall or support was found to be necessary. In this way, the bottom support is not provided alone by a limited or banded area, but by a maximum area, as represented by the flat or bearing bottom of a latch element. A further and highly important factor was found to arise from the standpoint of strength of and the aligned accuracy of the dual-support for the operating stem.

15 25 It has thus been an object of my invention to develop a new and improved form of latching or fastening device which will meet the limiting factors heretofore encountered and which will at the same time provide a new strength, safety and ease of operation;

30 Another object has been to not only prevent or minimize cross shear or lever action on a localized area of an operating stem for a latching device, but to do so without the necessity for an initial one-piece construction of latch housing with respect to its bottom wall;

35 35 A further object of my invention has been to develop a latch housing construction that may be made of any suitable material and that is particularly adaptable for the use of cast parts, although not limited thereto;

40 These and other objects of my invention will appear to those skilled in the art from the drawings and the specification.

In the drawings,

Figure 1 is a side view in elevation looking from a keeper-latching or open side of a mounted latching device constructed in accordance with my invention;

45 Figure 2 is a bottom plan of the latch part of Figure 1 and taken along the line II—II thereof; in this view, a latch element of the latching device is in a partially latched relationship with respect to a latch lug of a keeper;

50 Figure 3 is a vertical section taken along the line III—III of Figure 4 and on the same scale as Figures 1 to 4;

55 Figure 4 is a top plan view of a bottom plate member or wall element of the device of Figure 3; this element is shown in an at least semi-permanently, integrally mounted relationship with respect to a housing body in the construction of Figures 1 and 2;

60 Figure 5 is a fragmental vertical section taken in the direction of line VI—VI of Figure 2, on the same scale as that figure, and showing the housing body preliminary to the mounting of the under-plate member or element;

65 Figure 6 is a sectional fragment in elevation taken along the line VI—VI of Figure 2, showing the integrally assembled and secured relationship of the housing body and its under plate member or element.

In the figures, 10 represents a window sash, rail, door frame or other member of a pair of adjacent, relatively movable members that are to be securely latched and locked together. A keeper part 11 is secured in a substantially flush relation on one of the adjacent members by suitable means such as flat head screws 12 and has a downwardly-projecting latch lug 11b (see Figure 2) to

cooperate with and latch-receive a latching element 15 of an adjacently-positioned latching or fastening device 13. The device 13 has a one-piece housing body part provided with a pair of oppositely-projecting mounting feet, lug or tab portions 13a that have a common face plane. Each of the tab portions 13a has a pair of staggered mounting holes to receive suitable securing means, such as flat head screws 19. The means 19, as shown in Figure 1, project into the other adjacent member 10.

The keeper part 11 is not new to my present construction and a type such as shown in Figures 2A, 3 etc., of my Patent No. 2,135,105 may be used.

The housing body or part 13 of the latching device 13 has an upright or upwardly-projecting, enclosing side wall 13b of semi-circular shape about the part that is only open to and along the keeper 11. A top wall 13c projects substantially horizontally from and over the upright or side wall 13b to define a top enclosure for the one-piece housing body construction. A bearing support, mounting boss or inward projection 13d on the top wall serves as an upper support bearing for an upper annular or circular journal portion or area 14a of an operating stem of an operating means comprising a handle 14 and a stem extending substantially at right angles or perpendicular thereto.

Downwardly beyond the portion 14a, the stem has an angular, rectangular or square portion 14b to be cooperatively received within a complementary bore 15b of similar shape within latching element 15. The latching element 15, as shown particularly in Figures 1 and 2, has a latching surface wall 15a of increasing spiral height about a central spiral-like groove portion 15b. The portions 15a and 15b are those which cooperate with latch lug 11b of the keeper 11 to provide an increasing wedging-holding action as the device or its handle 14 is moved counterclockwise in Figure 2.

It will be noted that the complementary bore and stem portions 14b and 15b of angular section assure a positive turning of the latch element, irrespective of whether or not set screw 16 is tightened down. The function of the screw 16 is thus merely a superficial positioning one, as distinguished from a locking and a latching one, as would be the case were the bore of the latch element and the cooperating stem portion of the handle of circular shape.

Referring particularly to Figures 3 to 6, inclusive, the housing body part 13 has an especially constructed bottom side, such as to form an inset or under-set seating, mounting rim for a separately formed, shaped and conditioned bottom plate part, member or element 20. By making the part or plate member 20 separately, its inner face may be shaped and fabricated accurately and machined and honed down to provide a low frictional resistance or effective bearing type of support surface to journal the bottom face or end of latch element 15. Machining and other types of operations may be readily effected on the inside of the member or element 20 and a suitable fitted relationship between it and the latch element 15 may be accomplished before the plate 20 is permanently or semipermanently secured in an inset relation as an integral part to the under-shelf or ledge of the housing body 13. The bottom face of the plate 20 is then flush with or on the face plane of the mounting tabs 13a (see Figure 6).

To provide a secure and positive as well as an aligned mounting of the bottom plate member 20, I form a pair of downwardly-projecting pins, tits, nubbins or rivet extensions 13h. As a result, the element or member 20 may be accurately seated so that mounting holes 20b in the mounting tabs 20a fit on the projections 13h to thus provide aligning pairs between the members 13 and 20. In this connection, the bore of the holes 20b will very closely approximate the outer diameter of the projections 13h which are of annular or rounded form. Thus, as shown particularly in Figure 6, the projecting ends of

the rivet portions 13h may be hammered or peened down flush into suitably enlarged head-receiving outer portions of the holes 20b.

As shown particularly in Figures 3 and 4, opposed or opposite mounting lugs 20a which carry the holes 20b also enable the plate member 20 to be accurately aligned and to be easily fitted into and out of the under-opening in the bottom of the housing body 13 during the procedure of machining down, smoothing-off or honing the inner surface to receive and form a lower bearing, directly for the latch element 15, and indirectly for the lower end portion 14b of the stem. It also makes possible a substantially flush and a secure and fool-proof mounting of the member 20 from the standpoint of positively preventing a thief from gouging-out wood to the under-portion of the housing part, and then withdrawing the bottom plate downwardly in order to weaken the holding action of the latch part.

The latch element 15 has an inset journal portion or enlarged under-bore 15a that is open downwardly to receive and rest upon an upwardly-projecting bearing boss portion 20c of the member 20. It is apparent that the boss 20c, in cooperation with the portion 15a, in effect provides the alignment or turn axis for the handle 14 of the construction. As shown particularly in Figures 2 and 4, the location of the axis aligning boss 20c is off-center with respect to the housing body 13, as well as with respect to the outer or inclined wedge surface of the upright or side wall 13b.

30 This makes possible an increasing wedging action on the outer face 13b by turn-lock or adjustment screw 18, as is occasioned when the handle 14 is turned clockwise of Figure 2. In operation, the screw 18 (assuming that the latch operating arm is to the extreme right of Figure 2, so that the forward end of the latch element 15 has engaged with or has been stopped by limit wall or stop portion 13e) need only touch the surface or face 13b. This is true, since any attempt to move it towards an unlatching position will cause it to dig-in or wedge tightly. 35 This is also true, since in effect, an increasing projection of wedging surface is provided by the offset mounting of the latching element 15 with respect to its housing body 13.

40 Thus, in accordance with my invention, I have been able to provide a latch construction or fastening device whose housing body, in its final and completed form is integral in nature, and is of substantially one-piece construction. As preliminarily formed, the latch housing body is of two parts of a closely-interfitting, flush type and one of which defines an opposed bearing boss or mount with respect to the other, and by which the stem of the operating arm is positively and securely-operatively positioned therein. The latch element 15, itself, 45 is of somewhat thickened wall structure, to not only increase its strength from the standpoint of its latching action with the keeper lug 11b, but also from the standpoint of its utilization as a connecting and counter-pivot, counter-lever-action or shear-resisting member between the stem and particularly, the top and bottom walls of 50 the housing construction.

55 The under-fitted relationship of the bottom plate element or wall member not only complies with an important factor or requirement, namely a fully flush mounting of the latching device on its sash or mounting member 10, but also by the employment of projecting, rivet head pins, provides accurate means for aligning, positioning, and mounting the under-plate 20 as well as for securing it to the housing body 13 in a somewhat permanent manner, and in the manner that will adversely resist any 60 attempt by a thief or burglar to remove it.

65 What I claim is:

70 1. A fastening device for locking a pair of adjacently movable sash or like members in a secure relationship 75 with respect to each other, wherein a keeper is to be

mounted on one of the members and the fastening device is to be mounted adjacently thereto on the other member which comprises, a one-piece housing body, said housing body having foot tab portions to secure it on the other member in a cooperating relationship with the keeper, said housing body having a substantially semi-circular side wall portion projecting upwardly from between said foot tab portions and being open towards the keeper, said housing body having a top wall portion positioned over said side wall portion, a bearing mount in said top wall portion, an integral operating part having a handle and a stem projecting substantially perpendicular to said handle, said stem being constructed to project downwardly through said bearing mount and being journaled therein adjacent said handle, a latch shoulder element to be operatively mounted on said stem downwardly of said bearing mount within said housing and having a wedge-shaped latching surface to project through the opening in said side wall portion and latch with the keeper when turned into position with respect thereto, a bottom plate member having an upper bearing face and an upwardly-projecting bearing boss, pairs of cooperating aligning portions between said bottom plate member and said housing body, said bottom plate member being integrally mounted in an inset position on said housing body between said foot tab portions with its aligning portions in a cooperating relation and in a substantially flush relationship with bottom faces of said tab portions to provide a bottom wall portion for said housing, said latch shoulder element having an axial bore therethrough to receive said stem therein, said bore and said stem having cooperating portions to non-turnably secure said latching element on said stem, said latch shoulder element having a bottom bearing face journaled on the upper bearing face of said bottom plate member, and an upwardly-offset bearing enlargement in the bottom of said latch shoulder element in substantial alignment with said bore to receive within and to be journaled on said bearing boss when said bottom plate is integrally mounted in its inset position on said housing body.

2. A fastening device to be used with a keeper to be mounted on one member of a pair of adjacent relatively movable members to be latched in position with respect to each other which comprises, a one-piece housing body having a pair of oppositely-projecting foot tab portions on a common bottom face plane to receive mounting means and secure said housing body on the other member, said housing body having a substantially circular upright enclosing wall projecting from said foot tab por-

- tions and having an open side towards the keeper, said housing body having a top wall closing off said upright wall and having an axially-offset open portion therethrough, a bearing boss mounted about said open portion, 5 a bottom plate member having an axially-offset bearing boss projecting upwardly therefrom and having a pair of mounting tabs, said housing body having an inset mounting rim on its under-side that is inwardly-offset with respect to the face plane of said mounting tabs, means 10 projecting from a bottom portion of said housing body and cooperating with the mounting tabs of said bottom plate to secure said bottom plate as an integral part of said housing body in an opposed relationship with said top wall, a latching element of curvilinear shape having 15 a wedging face to engage the keeper, an angular bore through said latching element, an operating means having an integral handle and a stem projecting perpendicular thereto, said stem having angular portions to cooperate with and fit within the angular bore of said 20 latching element, so that a rotation of said handle will positively turn said latching element, said latching element having an open under-bearing recess portion therein in substantial alignment with said angular bore to receive the bearing boss of said plate member and rotatably rest 25 thereon, and an upper face of said bottom plate and its bearing boss defining bearing surfaces with a bottom face of and said under-bearing recess portion of said latching element.
3. A device as defined in claim 2 wherein, the upright 30 enclosing wall of said housing body has an inclined outer surface, and a locking element is adjustably carried by said handle to engage the inclined outer surface of said upright enclosing wall to lock said latching element in a latching position with the keeper.
- 35 4. A fastening device as defined in claim 3 wherein, said means that projects from the bottom portion of said housing body comprises downwardly-projecting pins, said bottom plate member has a pair of openings through its mounting tabs to receive said pins, and said bottom plate member is securely-integrally held in position within 40 in said housing body by rivet heads on said pins.
